(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof showing the detachable input element moved away from the base of the notebook computer with the drawing pad facing upward;

FIG. 9 is a perspective view thereof showing the detachable input element moved away from the base of the notebook computer with the keys facing upward;

FIG. 10 is a perspective view thereof showing the detachable input element put back into the base of the notebook computer with the keys facing upward;

FIG. 11 is a top view thereof showing the detachable input element put back into the base of the notebook computer with the keys facing upward;

FIG. 12 is an enlarged view of the portion, labeled '12' in FIG. 1;

FIG. 13 is an enlarged view of the portion, labeled '13' in FIG. 10; and,

FIG. 14 is an enlarged view of the portion, labeled '14' in FIG. 11.

The evenly dashed broken lines illustrate portions of the notebook computer that form no part of the claimed design. The unevenly dashed broken lines indicate enlarged portions of the notebook computer shown for clarity and form no part of the claimed design.

1 Claim, 12 Drawing Sheets
